PROCESS FOR PRODUCING GUANAMINE DERIVATIVES

Werner Zerweck and Walter Brunner, Frankfort-on-the-Main-Fechenheim, Germany; vested in the Alien Property Custodian

No Drawing. Application April 17, 1941, Serial No. 388,984. In Germany May 9, 1940

7 Claims. (Cl. 260—248)

Our present invention relates to an improved process for producing guanamine derivatives of the general formula:

wherein R stands for a member of the group consisting of an alkyl and the benzyl radicle, an aromatic radicle of the benzene and naphthalene series and a heterocyclic radicle of the furane series.

The present improved process consists in heating a mixture of dicyandiamide, a nitrile compound of the formula RCN, wherein R has the aforesaid significance, and a strongly basic compound.

When using nitrile compounds of a relatively low boiling point the reaction is advantageously carried out in a closed vessel.

Whereas the hitherto known processes convert the dicyandiamide into guanamines only in two steps or only with an insufficient yield, while considerable quantities of melamine and ammeline are formed as by-products, the present process yields in a single step the guanamine derivatives of the aforesaid formula with a excellent yield with practically no formation of undesired by-products.

The present guanamine derivatives are important intermediates for the production of valuable formaldehyde condensation products.

In order to further illustrate our invention the following examples are given, the parts being by weight and all temperatures in degrees centigrade.

Example 1

A mixture of 84 parts of dicyandiamide, 250 parts of acetonitrile and 16 parts of piperidine is heated for about 5 hours at about 190 to 195° in an autoclave. The crystallizing reaction product is 4,6-diamino-2-methyltriazine-1,3,5 (acetoguanamine):

The product has a melting point of 263° C. The yield obtained surpasses 80% of the theo-

retical, whereas without the addition of a basic compound such as piperidine there is obtained an impure reaction product melting at 200 to 216° C. in a yield of about 60% of the theoretical.

5 When adding 10 parts of ethylene-diamine instead of piperidine to the reaction mixture, a similar good result is obtained.

When replacing the acetonitrile by the equivalent amount of propionitrile, the 4,6-diamino-10 2-ethyltriazine-1,3,5 is obtained.

Example 2

A mixture of 84 parts of dicyandiamide, 250 parts of benzonitrile and about 8 parts of piperidine is heated for about 3 hours almost to the boiling point of the benzonitrile. 4,6-diamino-15 2-phenyltriazine-1,3,5 (benzoguanamine) of the formula:

20

25

crystallizes from the solution when cool. This product has a melting point of 222° and is obtained in a yield of 85% of the theoretical, whereas without the addition of piperidine only 30 a product containing about 25 per cent of melamine is obtained in a yield of about 40% of the theoretical.

The same result is obtained when heating to boiling a mixture of 42 parts of dicyandiamide, 55 parts of benzonitrile, about 75 parts of diethylbenzene and 4 parts of piperidine for about 3 hours.

Instead of piperidine corresponding amounts of other compounds of a strongly basic character such as diethylenetriamine, pyrrolidine, tetrahydroquinoline or potassium carbonate or sodium hydroxide may be added.

When replacing the benzonitrile by the equivalent amount of the three isomeric chlorobenzonitriles or methylbenzonitriles the corresponding substitution products of benzoguanamine are obtained bearing a chlorine atom or a methyl group in the ortho-, meta- or para-position of the benzene nucleus standing in the 2-position 50 of the triazine ring.

Example 3

A mixture of 300 parts of β -naphthonitrile, 84 parts of dicyandiamide, 3 to 5 parts of piperidine (or pyrrolidine or benzylamine) is heated while

stirring at 200 to 205° for 3 to 4 hours. When cool the reaction mass is diluted with an organic solvent of a low boiling point such as carbon tetrachloride and the precipitate is filtered off. The 4,6-diamino-2-(2'-naphthyl)-triazine of the formula:

thus obtained is a white powder having a melting point of 240° C. It is soluble in high boiling solvents such as benzonitrile. The yield is the theoretical whereas without the addition of a basic agent there is obtained a substantially smaller yield of a product of an inaccurate melting point and only partly soluble in benzonitrile.

is obtained. The same is a colorless powder melting at 248-250° C., soluble in hot water and scarcely soluble in alcohol and benzene.

We claim:

1. Improved process for producing guanamine derivatives of the general formula:

wherein R stands for a member of the group consisting of an alkyl and the benzyl radicle, an aromatic radicle of the benzene and naphthalene series and a heterocyclic radicle of the furane series which consists in heating a mixture of di-cyanamide, a nitrile compound of the formula RCN, wherein R has the aforesaid significance, and a strongly basic compound.

2. The process as defined in claim 1 wherein R is alkyl.

3. The process as defined in claim 1 wherein R is alkyl and wherein the strongly basic compound is a heterocyclic compound.

4. The process as defined in claim 1 wherein R is methyl and the strongly basic compound is piperidine.

5. The process as defined in claim 1 wherein R is an aryl of the benzene series.

6. The process as defined in claim 1 wherein R is phenyl and the strongly basic compound is piperidine.

7. The process as defined in claim 1 wherein R is naphthyl and the strongly basic compound is piperidine.

WERNER ZERWECK.
WALTER BRUNNER.

Example 4

A mixture of 84 parts of dicyandiamide, 250 parts of benzylcyanide and about 8 parts of piperidine is heated to boiling for about 3 hours. 4,6-diamino-2-benzyl-triazine-1,3,5 of the formula:

crystallizes from the solution when the solution is cool. The product melts at 232° melting point and is obtained in an excellent yield.

When using as a reaction component furonitrile the 4,6-diamino-2-furyl-triazine-1,3,5 of the formula:
